UNITED STATES PATENT OFFICE.

DONALD T. HASTINGS, OF DETROIT, MICHIGAN, ASSIGNEE TO HOLLEY BROTHERS COMPANY, OF DETROIT, MICHIGAN, A CORPORATION OF MICHIGAN.

AIR-WASHER.

1,272,434.

Specification of Letters Patent. Patented July 16, 1918.

Application filed March 8, 1917. Serial No. 153,273.

To all whom it may concern:

Be it known that I, DONALD T. HASTINGS, a citizen of the United States of America, residing at Detroit, in the county of Wayne 5 and State of Michigan, have invented certain new and useful Improvements in Air-Washers, of which the following is a specification, reference being had therein to the accompanying drawings.

10 The invention relates to air-washers designed for use in connection with carbureters and of that type in which the depth of immersion of the air-inlet is maintained constant by suitable means, such as a float. It 15 is the object of the present invention to provide an automatic signal or warning when the washing liquid is exhausted, thereby preventing injury to the motor through the use of dust-laden air. It is a further object to provide various features of advantage 20 as hereinafter set forth.

In the drawings:

Figure 1 is an elevation partly in vertical central section through the washer;

25 Fig. 2 is a plan view thereof.

A is the casing or receptacle for containing the washing fluid. This is preferably formed in two sections A and A', having a flanged engagement with each other and detachably connected by suitable means, such as the clamping-bolts B. The lower section 30 forms the receptacle for the liquid, while the upper section contains a series of annular baffle-plates C, D, E, F. G is an air-inlet tube extending vertically and centrally within the casing. H is an annular float on which the tube G is mounted by means of a suitable spider connection I, and the relation of these parts is such that the lower or discharge end of the tube is immersed in the liquid a predetermined distance below the normal level thereof. J is an air-outlet connection, preferably attached to the top or cover K of the casing and provided with 40 a depending tube L forming a guide bearing for the tube G, permitting a free sliding movement of the latter. Surrounding this tube is an annular opening M communicating with the section A' of the casing and 45 receiving the air therefrom after passing the baffles C, E and F.

50 With the construction as thus far described, when the washer is in operation the air drawn by the suction of the carbureter 55 will enter the tube G, passing downward

therethrough and depressing the liquid below its normal level so as to form in effect a return bend or passage. The dust in the air will be thrown into the liquid and will settle to the bottom of the receptacle, while 60 the dust-free air together with liquid carried in suspension will pass upward. The baffle-plates will remove the liquid so that only pure air will eventually pass into the outlet J and thence into the carbureter. By 65 reason of the fact that the air-inlet tube is supported by the float H, a constant relation is maintained between the same and the level of the liquid as long as there is any liquid in the receptacle; but in case the entire 70 supply should be exhausted the device would become inoperative and would deliver dust-laden air. It is important to guard against such a result, and I have therefore provided 75 automatic means for warning the operator of the inoperativeness of the washer. Preferably this warning is effected by shutting off the air supply, which through its effect on the carbureter and the operation of the engine will at once call attention to the 80 condition.

With the specific construction as shown, N is a bell or hood mounted on the upper end of the tube G, and surrounding the same with sufficient clearance to form an unrestricted inlet. The base of this bell is provided with a flange O, which when the tube is in its lowermost position, as where the water is exhausted, will seat upon a bearing P forming a closing valve. Normally the flange O is raised sufficiently above the seat to provide unrestricted inlet of the air, which after entering the bell passes through apertures Q in the side of the tube and thence downward; but, as above stated, when 90 the water is exhausted the flange will seat and cut off further inlet of air. It is necessary to provide for re-filling the receptacle with water, and it is also desirable to permit the continued operation of the carbureter and engine even where the washer is 95 inoperative the warning having been given. For this purpose I provide a filler tube R at the side of the section A of the casing, having a cap S for normally closing the 100 same, said cap being suitably locked as by the bail T. Thus whenever warning is given by the seating of the flange O and the shutting off of the air supply, the operator can 105 restore the device to operative condition by 110

opening the cap S and filling with water,— or, in case this is not available, by using the filler tube as an auxiliary air-inlet for rendering the carbureter operative. The receptacle A is also provided with a plug U in the bottom thereof, which may be removed for draining out the muddy water whenever necessary.

What I claim as my invention is:—

10 1. In an air-washer, the combination with a receptacle containing the washing liquid, of air inlet and outlet connections to said receptacle, a float for supporting the air inlet connection and for maintaining the same in constant relation to the level of the liquid, and means operated by said float for shutting off the air when the liquid has dropped to a predetermined level.

20 2. In an air-washer, the combination with a receptacle containing the washing fluid, of air inlet and outlet connections to said receptacle, a float for supporting the air inlet connection and automatically maintaining a constant relation between the same and the level of the liquid, and means carried by said air inlet connection for cutting off the air when lowered to a predetermined point.

30 3. In an air-washer, the combination with a receptacle containing the washing fluid, of a float within said receptacle, an air inlet tube carried by said float and having its discharge end maintained in constant relation to the level of the water, a hood carried by said inlet, and a seat coöoperating with said hood to close the inlet when the level of the liquid drops to a predetermined point.

40 4. In an air-washer, the combination with a receptacle containing the washing fluid, of air inlet and outlet connections, a float for adjustably supporting the air inlet connection and maintaining a constant relation be-

tween the same and the level of the liquid, means operating upon the dropping of the liquid level to a predetermined point for cutting off the supply of air, and auxiliary means for supplying air.

5. In an air-washer, the combination with a receptacle containing the washing fluid, of air inlet and outlet connections for said receptacle, a float for adjustably supporting the air inlet connection and maintaining the same in constant relation with the level of the liquid, means for automatically cutting off the air supply when the liquid level drops to a predetermined point, a filler for the liquid, and a removable cap for said filler permitting the use of the same as an auxiliary air inlet when the liquid is exhausted.

6. In an air-washer, the combination with a receptacle containing in the lower portion thereof the washing fluid, of air inlet and outlet connections, for said receptacle, a float for adjustably supporting the air inlet connection and maintaining the same in constant relation to the level of the liquid, means for automatically cutting off the air supply when the liquid level drops to a predetermined point, means for separating the liquid from the air located in said receptacle above the liquid level, a filler for the liquid located to limit the level of liquid introduced therethrough to below said separating means, and a removable closure for said filler permitting the use of the same as an auxiliary air inlet when the normal air inlet is cut off.

In testimony whereof I affix my signature 80 in presence of two witnesses.

DONALD T. HASTINGS.
